MARKING DEVICE

Oscar H. Molomot, Minneapolis, Minn., assignor to
Truckers Specialty Printing Co., Inc., Minneapolis,
Minn., a corporation of Minnesota

Filed July 24, 1958, Ser. No. 750,668

1 Claim. (Cl. 281—29)

The invention herein has relation to a novel and improved device useful for a variety of purposes but especially useful for the purpose of placing line markings on charts, commonly known as truck drivers' daily logs, which the Bureau of Motor Carriers of the U.S. Interstate Commerce Commission requires to be kept by each truck driver crossing a State line. This for the reason that the law requires a driver to have a stipulated number of hours of rest between driving assignments.

In practical operation, the charts, or drivers' daily logs, are of duplicate construction and bound together in tablet form. Each is constituted as a flat sheet of paper, or the like, having indicia thereon. More explicitly, the pertinent matter on each sheet is arranged in four vertically spaced, horizontal rows. The horizontal rows are, or could be entitled "Off Duty"; "Sleeper Berth"; "Driving"; "On Duty Not Driving"; and each title is followed by calibrations denoting a.m. and p.m. hours of a single day. Heretofore, truck drivers have marked up the charts or logs by placing thereon free hand horizontal lines to denote their time off duty, sleeping, driving and not driving, and vertical lines to denote their times of shift from category to category of the charts or logs. Usually, the line markings are duplicated, as by placing a sheet of carbon paper between two superimposed daily charts or logs. Free hand entry of the lines has been unsatisfactory because of irregularity and complication of the tabulation of the information. Verification of line markings evidently will be difficult, or even impossible, in instances when the lines are free hand, and thus carelessly drawn.

The device of the application renders the marking of status lines on the charts or logs easier for truck drivers and more readily and accurately decipherable than has heretofore been the case.

In the accompanying drawing forming a part of this specification,

FIG. 1 is a perspective view of a tablet having therein superimposed, detachable charts, each commonly known as a Driver's Daily Log, showing a marking device made according to the invention as when applied to use in the placing of line markings on an uppermost chart or log in or of the tablet;

FIG. 2 is a plan view of the disclosure of FIG. 1;

FIG. 3 is an enlarged sectional view, taken on line 3—3 in FIG. 1;

FIG. 4 is an enlarged bottom plan view of a marker of the marking device; and

FIG. 5 is a detail sectional view, taken on line 5—5 in FIG. 2.

Referring to the drawings and the numerals of reference thereon, 10 denotes a tablet having a plurality of duplicate superimposed charts or legs 11 therein. Each chart or log 11 is constituted as a flat sheet of paper, or the like, having indicia 12 thereon. The indicia on all of the charts, logs or sheets will be the same as the indicia on the uppermost sheet in FIG. 2 of the drawings, as well as identically situated. The charts, logs or sheets are detachable from the tablet along lines 13 extending transversely thereof at a single side of and equally spaced from the indicia.

In FIG. 2 of the drawings, the indicia 12 is arranged in four vertically spaced, horizontal rows. The upper-

2

most horizontal row reads "Off Duty." The next adjacent horizontal row reads "Sleeper Berth." The next adjacent horizontal row reads "Driving." The lowermost horizontal row reads "On Duty Not Driving." The heading or title of each row is followed by calibrations denoting the a.m. and p.m. hours, and parts thereof, of a single day. In practice, horizontal lines are drawn on the charts, logs or sheets with reference to the calibrations to denote the off duty, sleeping, driving and not driving times spent by truck drivers, and vertical lines are drawn to denote the times of shifting from one category to another, as from "off duty" to "driving," etc.

The new and improved marking device consists of an index board 14, of rectangular configuration as disclosed, and a marker 15, also rectangular, slidably assembled with said index board.

The index board 14 can be of any material suitable to its use. Desirably, it will be relatively thin, of uniform thickness and have rigidity. When to be put to use, said index board will be placed in superimposed relation to an uppermost chart, log or sheet 11 in the tablet 10, as in FIGS. 1 and 2 of the drawing, so that a rectangular opening 16 through the index board is aligned with and renders the indicia 12 discernible. Horizontal edges 17, 17 of said index board bounding or defining the opposite sides of the rectangular opening 16 are straight and parallel with each other.

Indicia on the upper surface of the marker 15 is the same as the indicia 12 on each chart, log or sheet 11, and will be identically situated with respect to the calibrations on the charts, logs or sheets denoting the a.m. and p.m. hours when the index board and said marker are superimposed upon an uppermost chart, log or sheet. Said index board and the marker can be situated in superimposed relation to the charts, logs or sheets in any suitable and convenient manner. As disclosed, a cover of or for the tablet includes upper and lower flaps, denoted 18 and 19, respectively, and the index board is integral, as at 20, with an end of the lower flap 19 spaced from the tear lines 13.

The marker 15 can be of any material suitable to its purpose. Desirably, it will be relatively thin and have rigidity. As disclosed, said marker consists of transparent plastic or composition material, so-called. A body 21 of the marker is relatively flat, and each of opposite end portions of said marker is constituted as a centrally disposed, outwardly extending flange 22 and a pair of transversely spaced, outwardly extending flanges each denoted 23. The flanges 23 at each end of the body 21 are in a single plane substantially parallel with the plane of said body, the flange 22 at each end of the body is between and in spaced, parallel relation to the flanges 23 at the same end of said body, and, together, the flanges 23, 22, 23 at each end of the body provide an outwardly opening guideway 24. The guideways 24, in the plane of the body 21 of the marker and in oppositely facing relation, are for snugly receiving interiorly extending, marginal edge portions 25, 25 of the index board 14 which terminate in the horizontal edges 17, 17 thereof. The construction and arrangement will be such that when the index board 14 and the marker 15 are assembled, the horizontal edges 17, 17 of said index board will be adjacent to the opposite ends of the body 21, as in FIG. 3 of the drawing, and said marker will be manually slidable longitudinally along the index board relative to the calibrations on the charts, logs or sheets 11 in the tablet. The opposite side edges 26, 26 of the marker will be in perpendicular relation to the index board transversely thereof when said marker and index board are in assembled relation.

Vertically spaced apertures through the marker 15 are

indicated 27, 28, 29 and 30 respectively. The apertures 27 are longitudinally aligned with the title "Off Duty" and the calibrations corresponding thereto. The apertures 28 are longitudinally aligned with the title "Sleeper Berth" and its calibrations. The apertures 29 are longitudinally aligned with the title "Driving" and its calibrations. And the apertures 30 are longitudinally aligned with the title "On Duty Not Driving" and its calibrations.

Transversely spaced, longitudinally extending ridges, each represented 31, on the lower surface of the transparent marker 15 are aligned with the sets of vertical apertures 27, 28, 29, 30, respectively.

The manner of use of the marking device will be apparent. When "off duty" time is to be entered on a chart, log or sheet, a pencil, or other writing implement, will be inserted through an aperture 27 and caused to draw a longitudinal line on the chart, log or sheet concurrently with manual horizontal sliding movement of the marker. When "sleeper berth" time is to be recorded, the writing implement will be placed in an aperture 28 and caused to draw a longitudinal line with manual horizontal sliding movement of the marker. "Driving" time and "on duty not driving" time will be marked up while the writing implement is in apertures 29 and 30, respectively.

When, at the expiration of any of the conditions denoted by the titles, a shift of category is to be made, the marker will be slid longitudinally of the index board to situate a side edge 26 of said marker at the appropriate position to serve as a straight edge or guide for directing a manually manipulated writing implement to travel transversely, upwardly or downwardly as the case may be, of the calibrations on a chart, log or sheet.

The transversely spaced, longitudinally extending ridges 31 retain the body 21 and flanges 22, 23 of the marker 15 in spaced relation to a chart, log or sheet while a writing implement is operative thereon, thus to lessen liability of blotting when recording is done in ink. And, too, said ridges constitute or provide scribe lines by employment of which the apertures can be accurately located with respect to the calibrations on the charts, logs or sheets.

What is claimed is:

A truckers' log book consisting of a plurality of identically sized chart sheets each having an identical longitudinally extending rectangular chart displayed thereon, 5 a cover having a flexible upper flap and a flexible lower flap each of substantially the same dimensions as that of said chart sheets, means binding said upper and lower flaps and said sheets together along a first transverse edge of said log book, said sheets being provided with perforations to facilitate removal parallel to and adjacent said first edge, a flexible index flap integral with said lower flap at a second transverse edge thereof, parallel to and spaced from said first edge, said index flap being of substantially the same dimension as said upper and lower flap and said chart sheets and being foldable to lie in superimposed relation to an upper surface of an uppermost one of said sheets and to lie in spaced relation to said uppermost sheets, said index flap being provided with an elongated, rectangular, longitudinally extending opening positioned to align with said chart on said uppermost chart sheet when said index flap is positioned in superimposed relation thereto, said opening being partially bounded by parallel, facing longitudinal edge portions of said index flap, and a marking guide constituted as a body 20 extending transversely of said index flap and outwardly extending flanges on opposite ends, respectively, of said body providing outwardly opening guideways substantially in the plane of the body and slidably receiving said longitudinal edge portions of said index flap, said marking guide being provided with a plurality of pencil receiving holes therethrough and with at least one straight edge portion extending perpendicularly to said longitudinal index flap edge portions.
